OCARINA

George A. Mausolf, Waterbury, Conn., assignor to
 The Waterbury Button Company, Waterbury,
 Conn., a corporation of Connecticut

Application June 30, 1938, Serial No. 216,711

3 Claims. (Cl. 84—380)

This invention relates to musical instruments and more particularly to an improvement in an ocarina.

One object of the present invention is to provide an ocarina constructed of two perforated molded halves tightly sealed together at their abutting edges and which are preferably made from a plastic molding compound such as "Bakelite", cellulose acetate, etc.

Another object is to provide an ocarina in which the mouthpiece thereof has a semi-circular interior air passage bounded by a circular groove in one molded half, and a flat metal strip inserted between both halves of said mouthpiece.

Other objects include the provision of a flange or rib on the edge of one of the halves adapted to interfit with a smooth edge on the other half; the provision of means to lock the metal insert in position between the halves; and the provision of locating posts and a groove to maintain the metal insert in proper position in respect to a main outlet opening in one of said halves whereby musical notes may be produced when air is blown through the semi-circular passage of the mouthpiece.

A further object is to provide an ocarina of the above nature which will be simple in construction, inexpensive to manufacture, readily manipulated, compact, ornamental in appearance, and very efficient and durable in use.

With these and other objects in view there has been illustrated in the accompanying drawing one form in which the invention may be conveniently embodied in practice.

In the drawing:

Fig. 1 is a perspective view of an ocarina embodying the principles and features of this invention, and indicating in dotted lines the playing position of the user's fingers.

Fig. 2 is a cross-sectional view of the same taken on the line 2—2 of Fig. 1 through the mouthpiece.

Fig. 3 is an inside plan view of one of the halves of the ocarina.

Fig. 4 is an inside plan view of the other half of the ocarina.

Fig. 5 is a cross-sectional view of the mouthpiece, taken on the line 5—5 of Fig. 2 at right-angles to the metal insert.

Fig. 6 is a top plan view of the ocarina.

Referring now to the drawing wherein like reference characters designate corresponding parts throughout the several views, the numeral 10 designates the top molded half and the numeral 11 designates the bottom half of the improved ocarina. The top half 10 is provided with

a mouthpiece portion 12, and an oval shaped body portion having a plurality of finger openings 13, 14, 15, 16, 17, 18, 19 and 20 adapted to be covered by the fingers of both hands, as shown in Fig. 1. These openings may be labeled with suitable indicia such as the words shown in Fig. 6 to indicate which musical note will be produced when any particular opening and those preceding it are uncovered as in the usual ocarina. When all of the openings 13—20 are covered, the musical note "C" or "do" will be produced when the player blows into the mouthpiece. When the opening 13 is uncovered the note "D" or "re", will be produced, and by additionally uncovering the opening 14 an "E" note, or "mi", will be produced, etc. The curved wall of the top half 10 and its mouthpiece portion 12 terminates in a flat smooth edge 21 which is adapted to interfit with a flanged edge 22, formed on the bottom half 11.

The lower half 11 has a mouthpiece portion 23 for cooperating with the portion 12 on the top half 10. The body of the lower half 11 has a pair of thumb openings 24 and 25 and a central main opening 26 formed therein, and the flanged edge 22 of said half is provided with an interior rib 27, 28 which is adapted to fit within the unflanged edge 21 of the top half 10 to position the two halves 10 and 11 with respect to each other so that when the ocarina is assembled, the respective edges 21 and 22 will be in tight abutment.

In order to form a semi-circular air passage in the mouthpiece portion 23 of the bottom half 11, said half 11 is provided with a pair of spaced cylindrical insert-holding posts 28 and 29, disposed on opposite sides of the main opening 26 (as shown in Figs. 2, 3 and 5). The mouthpiece portion 23 has an elongated tapered groove 30, semi-circular in cross-section, which extends throughout its length and terminates just short of the outlet opening 26—preferably flattening out somewhat as it approaches said opening 26.

Provision is also made at the sides of said tapered groove 30 of a pair of guide slots 31 and 32, to provide seating shoulders 33 and 34 for the side edge of a metal insert strip 35 which is adapted to be maintained thereby in a predetermined spaced relationship in respect to the groove 30 forming therewith a substantially semi-circular air passage.

The corners at the inner end of the insert strip are adapted to seat in notches 36 and 37 provided therefor in the posts 28 and 29 respectively. The outer end of the strip 35 is reduced in width and is adapted to seat in a notch 38.

38 provided in the wall 21 of the mouthpiece portion 12 of the top half 10.

By means of this construction, it will be noted that when the halves 10 and 11 are assembled, the insert strip 35 will be securely locked in place, being properly located in respect to the main outlet opening 26 by the posts 28 and 29, and held against outward movement by the notched end 38 of the top mouthpiece portion 12.

10 Before assembling the two halves 10 and 11 of the ocarina, the edges 21 and 22 thereof will preferably be coated with a suitable cement so that a tightly sealed joint will be formed therebetween, when the halves are pressed together.

15 One advantage of the improved ocarina herein disclosed is that it is very light in weight, may be made of colored molded material requiring no enamel, paint or other exterior finish, and will have a smooth non-chippable exterior surface.

20 While there has been disclosed in this specification one form in which the invention may be conveniently embodied in practice, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

30 Having thus fully described the invention, what is claimed as new and for which it is desired to secure Letters Patent, is:

1. In an ocarina, a pair of complementary hollow sections, each having a flat peripheral edge shaped to abut against each other, one of said sec-

tions having an interior rib to interfit within the edge of the other section, said sections having aligned interfitting portions extending therefrom to form a mouthpiece, one of said sections having a central main outlet opening in alignment with and at the inner end of said mouthpiece, a flat partition in said mouthpiece, one side of said partition forming an air blowing passage.

2. In an ocarina, a pair of complementary perforated hollow sections, each having a flat edge about its periphery shaped to abut against each other and cemented together, said sections having complementary aligned interfitting projecting portions to form a mouthpiece, one of said sections having a central main outlet opening located adjacent the inner end of said mouthpiece, a flat strip of metal in said mouthpiece forming one side of an air blowing passage, the outer ends of said mouthpiece sections engaging said metal strip to hold it in position in said mouthpiece.

3. In an ocarina, a pair of complementary oval shaped hollow sections having tightly sealed edges, a mouthpiece comprising complementary aligned projections on said sections, one of said projections having a mouthpiece which is provided with an inwardly tapered air passage, said passage being substantially semi-circular in cross-section and leading to the interior of said instrument, a flat partition covering one side of said passage and held between said hollow sections, and a pair of upstanding notched posts at the inner end of said tapered passage for cooperating with said mouthpiece sections for holding said partition in position.
